RAILWAY TRUCK

Donald S. Barrows, Rochester, N. Y., assignor to
The Symington-Gould Corporation, Depew,
N. Y., a corporation of Maryland

Application September 11, 1944, Serial No. 553,623

20 Claims. (Cl. 188—190)

1

This invention relates to a railway truck and more particularly to a brake beam support therefore.

An object of the invention is the provision, in a railway truck, of a brake beam hanger arranged for movement relative to a side frame so as to maintain a brake shoe in a fixed position relative to an associated wheel.

Another object of the invention is the provision, in a railway truck in which a side frame moves vertically with respect to a supporting journal box, of a brake hanger bracket arranged for movement to compensate for the movement between the side frame and journal box.

A further object of the invention is to provide in a railway truck, a brake hanger jaw arranged for vertical movement in a direction opposed to a vertical movement of a side frame relative to a supporting journal box.

A still further object of the invention is to arrange a brake hanger jaw supported by a vertically movable side frame in such a manner so that the brake hanger jaw will approximate in the opposite direction, a vertical movement of the side frame relative to a journal box.

These and other objects of the invention will become apparent from the succeeding description considered together with the accompanying drawings, the latter of which disclose two species embodying the present invention, and wherein:

Figure 1 is a partial vertical sectional and elevational view of a railway truck illustrating a form of the invention.

Figure 2 is a partial horizontal sectional and plan view of the railway truck shown in Figure 1, and being taken approximately along the lines 2—2 of Figure 1, looking in the direction of the arrows.

Figure 3 is an enlarged cross sectional view taken along the lines 3—3 of Figure 1, looking in the direction of the arrows.

Figure 4 is an enlarged cross sectional view taken along the lines 4—4 of Figure 1, looking in the direction of the arrows.

Figure 5 is a partial vertical sectional and elevational view of a railway truck embodying a second species of the invention.

Figure 6 is a horizontal view of the railway truck shown in Figure 5, and being taken approximately along the lines 6—6 of Figure 5, looking in the direction of the arrows.

Figure 7 is an enlarged sectional view taken along the line 7—7 of Figure 5, looking in the direction of the arrows.

Figure 8 is an enlarged sectional view taken along the lines 8—8 of Figure 6, looking in the direction of the arrows.

Referring now in detail to Figures 1 to 4 of the drawings, which disclose one embodiment of the invention and wherein like reference characters indicate like parts, the numeral 1 is em-

ployed to designate in a general manner a railway truck, only a portion of which is illustrated. The railway truck comprises a pair of side frames 2 and a usual connecting resiliently supported bolster 3, only a portion of one side frame and a portion of one end of the bolster being illustrated because the undisclosed portions of the truck are counterparts of the disclosed quarter portion thereof. One end 4 of the side frame is provided with downwardly opening jaws 5 within which is a journal box 6 arranged to be carried by a wheel and axle assembly 7. Because of the bearings (not shown) between the axle and journal box and housed by the latter to afford a free rotative action of the wheel and axle assembly, the horizontal axis of the assembly does not vary vertically with respect to the journal box, that is to say, the relationship between the horizontal axis of the assembly and the journal box remains constant vertically throughout the entire range of service movements of the truck. Since the wheel of the assembly travels along a rail 8 the vertical relationship between the rail, wheel and axle assembly and journal box also remains at all times constant.

In order to present an easy riding truck capable of service in high speeds, the side frame is resiliently supported by the journal box so that any external impulses imparted to the wheel and axle assembly will be cushioned and the complete forces will not be imparted to the side frame, bolster and car body. As exemplary of a means for affording a resilient support for the side frame there is provided a deformable resilient element 9 positioned on a roof 10 of the journal box with an inverted U-shaped yoke 11 straddling the journal box with an upper web portion 12 bearing upon the resilient element. Depending from each end of the yoke web is an arm or hanger element 13 closely associated with a side of the journal box and terminating adjacent its lower limits in a horizontal shelf or seat 14 directed away from the journal box. Mounted upon each shelf or seat is a coil or helical spring 15 arranged to act vertically and having its upper end engaging a downwardly facing ledge 16 formed on the side frame in vertical alignment with the related shelf and its lower end bearing upon the shelf. Accordingly, any load transmitted to the side frame through the bolster end and related springs will pass through the side frame and the helical springs 15 to the hanger element and thus through the resilient element 9 to the journal box and wheel and axle assembly. Thus the side frame extremity is arranged to move vertically relative to the supporting journal box. This oftentimes desirable resilient support for the side frame causes an undesirable feature in a railway truck, particularly when a brake hanger bracket is formed integrally with the side frame.

As will be observed, and as previously stated, the axis of the wheel and axle assembly remains at all times constant with respect to a supporting rail while the side frame is arranged to move vertically with respect thereto. If in the latter considered truck the brake hanger bracket is formed integral with and therefore remains constant with respect to the side frame, a brake hanger suspended from the bracket will also move vertically with respect to the wheel and axle assembly, resulting in a constant vertical shifting of the brake beam. In a preferred position, the brake beam, inclusive of a brake head and wheel contacting shoe, is arranged so that the latter will move, during brake release and application, approximately in a path which, when extended, will bisect the axis of the wheel and axle assembly. This path may be or approximate an inclination of 12 degrees with respect to a horizontal plane passing through the axis of the wheel and axle assembly and, as previously stated, radiating from said axis. The brake beam, therefore, should remain constant or substantially so with respect to the wheel and axle assembly so that among numerous other reasons, if the truck is in transit and the brakes are applied, particularly when the side frame supporting springs have been compressed, the brake rigging, upon recoil of the side frame supporting springs, will not be subjected to abnormal stresses.

As exemplary of a means to maintain a brake beam in a substantially constant relation with respect to the axis of the wheel and axle assembly, there is provided an adjustable brake beam support designated generally by the reference 17 and comprising a housing 18 formed integrally with and upstanding from the yoke web. The housing forming a complete enclosure, but, however, opening longitudinally of the truck, is positioned desirably on the vertical axis of the journal box so as to reflect a true, vertical movement between the journal box and side frame. The side frame, in the area above the journal box, is provided with oppositely and transversely spaced bosses 19 and 19a formed in the outer and inner side flanges 20 and 20a respectively of the compression member 21. The outer boss 19 is provided with a round aperture 22 while the inner boss 19a has a round opening 23 of less diameter than the aperture. However, both the aperture and opening have a common axis. Bisecting the compression member is a shaft 24 having a collar outer extremity 25 journaled in the outer boss and spaced longitudinally therefrom is a reduced neck 26 journaled in the inner boss. By reason of this stepped arrangement in the shaft the latter is prevented from shifting inwardly of the truck from its illustrated or normal position. A U-shaped strap 27 is formed integrally with the outer flange of the compression member and is provided with a circular opening 27a in axial alignment with and of the same diameter as the aperture 22 so that the shaft, during assembly, may be threaded through the circular opening into the side frame. A clip 28 having upturned ends is disposed between the strap and outer flange of the compression member to form a barrier against or arrest an unwarranted or accidental displacement of the shaft and thereby retain it in operable position. The shaft between the neck and collar is formed square in cross section as at 30 with the corners preferably rounded so that the intermediate section 30 may be considered as being inscribed within the circular dimensions of the collar. This, therefore,

will permit the shaft to be inserted into the side frame. Associated with the shaft is an arm 31 having a hub 32 cored to neatly accommodate the intermediate portion of the shaft so as to pivot the shaft about its axis. The arm extends normally horizontally from the shaft to terminate in a cylindrical or drum-shaped extremity 33 disposed within the housing and having its axis coincide with the vertical axis of the journal box. A resilient element, means or leaf spring 34 is interlocked with the housing to bear vertically against the cylindrical arm extremity and maintain the latter in bearing relation with the housing. The leaf spring functions as an anti-rattling device as well as preventing lost motion between the arm and housing. From the above it will be noted that any vertical movement of the side frame relative to the journal box will be reflected in a pivotal movement of the shaft.

The shaft, inwardly of the truck beyond the neck, is again formed of square cross section as at 35 with this squared section being of such proportions as to pass through the round opening 23 and facilitate assembly of the shaft with the side frame. Instanding of the truck horizontally from the inner compression member flange is an L-shaped auxiliary bracket 36 presenting an apertured leg 37 parallel with but spaced inwardly from the compression member. An inner extremity 38 of the shaft occupies the aperture of the auxiliary bracket leg and this arrangement forms not only an innermost support for the shaft but defines an area 39 between the bracket leg and compression member. Confined within the area 39 is a butt 40 of a lever 41 suitably cored to accommodate neatly the shaft squared section 35 so that any rotative movement of the shaft will be transmitted immediately to the lever. The lever extends from the shaft in an inclined vertical direction to terminate in a jaw 42.

Extending inwardly of the truck from a column 43 thereof which defines one side of a bolster accommodating opening 44, is a bracket 45 preferably formed integral with the column and being directed transversely of the truck. The bracket 45 is desirably U-shaped in transverse elevation and as such comprises an outer apertured base 46 and a lower connecting horizontal bar 47 which terminates at its free or inner extremity in an upwardly directed or apertured vertical bearing 48. The horizontal bar is desirably of inverted U-shape in vertical cross section to rigidify the bracket against stresses to which it will be subjected in service. Extending through horizontally aligned apertures in the base and bearing is a rod or stub axle 49 prevented from shifting outwardly of the truck by the compression member inner flange and inwardly of the truck by an arresting removable clip 50 interlocked with the vertical bearing. Pivotally mounted on the stub axle between the bracket base and bearing is a movable means 51 arranged to carry a brake hanger and brake beam assembly 52. The movable means is desirably formed as a unitary element comprising a tubular shank 53 neatly accommodating the stub axle and having extending from the compression member adjacent extremity an integral lever 54 directed vertically at an inclination corresponding to the inclination of the lever 41. That is to say, the axis of the lever 54 is preferably parallel to the axis of the lever 41 so that the levers point in the same direction and any rotative movement of the shaft will be reflected in a corresponding rotative movement of the tubular shank. The

free extremity of the lever 54 is formed as an open jaw 55 preferably in longitudinal alignment with the lever jaw 42 with both jaws pivotally connected by a rod, rigid tie or link 56, the latter of which is in parallel relation with and positioned inwardly of the truck from and adjacent to the compression member. Extending horizontally from and formed integral with the tubular shank is a hanger jaw or U-shaped hanger support 57 directed toward the associated extremity of the side frame. The hanger support has its free extremity formed by spaced upper and lower fingers 58 defining a recess 59 therebetween so that the hanger of the hanger and brake beam assembly may be positioned in the recess to suspend the assembly from the unitary element or movable means 51. Vertically aligned apertures 60 are formed in the hanger jaw fingers for the reception of a bolt means to prevent an accidental displacement of the hanger and brake beam assembly.

Because of the particular arrangement and disposition of the various components above described it will be noted that as the side frame moves downwardly relative to the journal box, the shaft and stub axle will be carried downwardly a corresponding distance. However, this movement will result in a rotative movement in a clockwise direction being imparted to the shaft to be reflected in a corresponding rotative movement of the tubular shank. These movements, therefore, will result in the hanger jaw being raised an amount corresponding to the downward movement of the side frame to thereby maintain the brake hanger and brake beam assembly in an adequately supported fixed position relative to the wheel and axle assembly. In other words, the arrangement of components is such that a movement of the side frame in one direction will be reflected in a corresponding or like movement of the brake hanger jaw in an opposite direction.

Referring now in detail to Figures 5 through 8 of the drawings which disclose a modified form of the invention, a railway truck 1a (only a portion of which is shown) comprises a side frame 2a and the usual bolster or load carrying member 3a. The journal box 6a and journal box mounting 9a and 15a are substantially the same in the design under immediate consideration as to corresponding structure or components of the previously described design excepting that a spring seat or shelf 14a of a hanger element 13a is provided with a depending lug or housing 18a formed in part by a clip like member 62 apertured to receive a horizontal transversely extending retaining pin or key 63 which is parallel with and spaced below the related shelf. The key has an L-shaped head 64 formed on one end thereof and which is disposed within the channel-like clip to be removably secured therein by any means such as the pin 65 insertible through aligned openings. Disposed oppositely or inwardly of the truck from the clip is a boss or jaw 66 apertured so as to be bisected by the free extremity of the key for the purpose to be hereinafter pointed out.

As will become hereinafter apparent, the clip and lower jaw may be formed integral with a lower extremity of the journal box in the absence of a yoke 11a in the truck structure but, however, the side frame still being resiliently supported from a journal box 6a wherein the shelves are made integral with the journal box or wherein a coil or other spring is interposed between the

top of the journal box and overlying portion of the side frame. In this latter instance the clip and lower jaw, and possibly only the lower jaw, may be formed as a part of the journal box just as long as it is arranged to move vertically with the journal box or reflect any vertical action thereof.

Projecting inwardly of the truck from preferably an upper extremity of a column 43a of the side frame is a bracket 45a of substantially U configuration in transverse elevation and comprising a boss 46a having extending therefrom a lower connecting bar 47a terminating in an apertured upstanding bearing 48a. Bridging the space between the boss and bearing in upper spaced relation to the connecting bar is a stub axle 49 disposed within the apertures of the boss and bearing and retained in operable position by a removable retaining means 50a. Pivotally associated with the stub axle intermediate the ends thereof is a movable means 51a arranged to carry a brake hanger and brake beam assembly 52a. The movable means comprises a tubular shank 53a sleeved over the stub axle and arranged to pivot relatively thereto. Outstanding from one or the side frame adjacent extremity of the tubular member is an integral upper jaw type lever 54a directed at an upwardly inclined direction toward the associated extremity of the side frame. A jaw 55a of the lever opens downwardly towards the upper jaw 66 and both jaws are pivotally connected by a rod, rigid tie or link 56a, the latter of which extends diagonally from adjacent the lower extremity of the journal box upwardly toward the upper extremity of a related column. The link is disposed parallel to the side frame inwardly therefrom in the present illustration. However, in the case of an inboard truck the link will be disposed outwardly of the side frame with its connected components transposed accordingly.

Extending horizontally from and formed integral with the tubular shank is a hanger jaw or U-shaped hanger support 57a directed away from the shank toward a related end of the side frame. The hanger support is similar to the hanger support 57 of the previously described structure and, accordingly, functions as a carrier for the brake beam assembly 52a.

By briefly considering the present design, it will be noted that any downward movement of the side frame relative to the journal box which will change the vertical relationship between the wheel and axle assembly 1a and the side frame, the tubular shank will, through the medium of the tie, be rotated in a clockwise direction to alter the relationship between the jaw 57a and the side frame and thereby maintain the brake beam assembly in a fixed position relative to the wheel and axle assembly.

From the above it will be noted that various changes and alterations may be made to the illustrated and described constructions without departing from within the spirit and scope of the appended claims.

I claim:

1. In a railway truck having a resiliently mounted side frame carried by a journal box and a wheel of a wheel and axle assembly, the combination of, a bracket carried by the side frame, a brake hanger jaw pivoted directly to and movable with respect to said bracket, said brake hanger jaw being in alignment with said wheel for supporting a brake beam and actuating means for pivoting said brake hanger jaw in one

direction when the side frame moves relative to the journal box in the opposite direction for maintaining a constant relationship between said brake beam and wheel.

2. In a railway truck having a resiliently mounted side frame carried by a journal box and a wheel of a wheel and axle assembly, the combination of, means pivotally mounted directly on a column of said side frame and including a brake hanger jaw, said brake hanger jaw being in alignment with said wheel for supporting a brake shoe, means movably connected to said journal box, and means connecting both of said means so that movement between said journal box and side frame will be reflected in said jaw for maintaining a constant relationship between said brake shoe and wheel.

3. In a railway truck having a resiliently mounted side frame carried by a journal box and a wheel of a wheel and axle assembly, the combination of, means carried by and arranged to move relative to a column of said side frame, said means comprising a brake hanger jaw in substantial radial alignment with said wheel for supporting a brake shoe, movable means connected to said journal box, and connecting means extending between said first two named means; all of said means being so arranged and constructed that a movement of the side frame in one direction will be reflected in an equal movement of said jaw in the opposite direction for maintaining a substantially constant relationship between said brake shoe and wheel.

4. In a railway truck having a side frame vertically movable with respect to a related journal box and wheel, the combination of, pivotal means instancing from a column of said side frame, means including a brake hanger jaw mounted on said pivotal means, said brake hanger jaw being in substantial alignment with said wheel for supporting a brake beam, means connected to said journal box, and means connecting said last two named means so that a relative vertical movement between said journal box and side frame will be reflected in said jaw for maintaining a constant relationship between said brake beam and wheel.

5. In a railway truck having a resiliently mounted side frame carried by a journal box and a related wheel, the combination of, support means extending inwardly of said truck from a side frame column, movable means mounted on said support means including a brake hanger jaw for carrying a brake beam, and means connecting said journal box and movable means; both of said last named means being so arranged and constructed that vertical movement of said side frame relative to said journal box in one direction will be reflected in said jaw in an opposite direction for maintaining a substantially constant relationship between said brake beam and wheel.

6. In a railway truck having a resiliently mounted side frame carried by a journal box and a related wheel, the combination of, movable means supported from a guide column of said side frame inwardly of said truck, said means including a brake hanger jaw arranged to carry a brake beam, and means connecting a movable element of said truck and said movable means, all of said means being so arranged and constructed that movement of said side frame relative to said journal box in one direction will be approximated by a movement of said jaw in the opposite direction for maintaining a substantially

constant relationship between said brake beam and wheel.

7. In a railway truck having a resiliently mounted side frame carried by a journal box and a related wheel, the combination of, an arrangement for maintaining a constant relationship between a brake beam and said wheel comprising a bracket extending inwardly of said truck from a guide column of said side frame, means comprising a brake hanger jaw pivotally mounted on said bracket, said brake hanger jaw being adapted to support said brake beam, means pivotally mounted on said side frame removed from said first named means, connecting means joining said first and second named means, and means connecting said journal box and second named means.

8. In a railway truck having a resiliently mounted side frame carried by a journal box and a related wheel, the combination of, an arrangement for maintaining a constant relationship between a brake beam and said wheel comprising a bracket formed integrally with the column of said side frame, pivot means carried by said bracket, lever means mounted on said pivot means, a brake hanger jaw movable with said lever means, said brake hanger jaw being adapted to support said brake beam, a lever arrangement connected to said journal box and pivotally mounted on said side frame at a location removed from said bracket, and link means connecting said lever means and lever arrangement.

9. In a railway truck having a resiliently mounted side frame carried by a journal box and a wheel, the combination of, an arrangement for maintaining a constant relationship between a brake beam and said wheel comprising a lever means arranged to pivot about a horizontal axis and carried by said side frame, a brake hanger jaw formed integrally with said lever means, said brake hanger jaw being adapted to support said brake beam, a lever arrangement pivotal about a horizontal axis and connected to said journal box, and link means connecting said lever means and lever arrangement.

10. In a railway truck having a resiliently mounted side frame carried by a journal box and a wheel, the combination of, an arrangement for maintaining a constant relationship between a brake beam and said wheel comprising a lever means arranged to pivot about a horizontal axis and carried by said side frame, said lever means comprising a horizontally directed brake hanger jaw and a vertically directed arm, said brake hanger jaw being adapted to support said brake beam, a lever arrangement pivotal about a horizontal axis and connected to said journal box, and link means connecting said lever arrangement and arm.

11. In a railway truck having a resiliently mounted side frame carried by a journal box and a wheel, the combination of, a lever means arranged to pivot about a horizontal axis and carried by said side frame, said lever means comprising a horizontally directed brake hanger jaw for supporting a brake beam and a vertically directed arm, a shaft pivotal with respect to and carried by said side frame, horizontal means secured to said shaft and arranged to pivot said shaft upon movement between said side frame and journal box, and means connecting said shaft and arm so that movement of said horizontal means will be reflected in a movement of said jaw to main-

tain a substantially constant relationship between said brake beam and wheel.

12. In a railway truck having a resiliently mounted side frame carried by a journal box and a wheel, the combination of, an arrangement for maintaining a constant relationship between a brake beam and said wheel comprising a lever means arranged to pivot about a horizontal axis and carried by said side frame, said lever means comprising a horizontally directed brake hanger jaw and a vertically directed arm, said brake hanger jaw being adapted to support said brake beam, a shaft pivotal with respect to and carried by said side frame, horizontal means secured to said shaft and arranged to pivot said shaft upon movement between said side frame and journal box, vertically disposed means secured to said shaft, and means connecting said vertically disposed means and arm.

13. In a railway truck having a resiliently mounted side frame carried by a journal box and a wheel, the combination of, a bracket formed integrally with a column of a side frame and extending inwardly of the truck therefrom, a pivot pin carried by said bracket, means carried by said pivot pin and arranged to move relatively to said bracket, a jaw facing toward an end of said side frame and formed in said means for supporting a brake beam, and means connecting said journal box and first named means so that a movement of said side frame relative to said journal box in one direction will be reflected in a movement of said jaw in the opposite direction for maintaining a constant relationship between said brake beam and wheel.

14. In a railway truck having a resiliently mounted side frame carried by a journal box and a wheel, the combination of, a bracket formed integrally with a column of a side frame and extending inwardly of the truck therefrom, pivot means carried by said bracket, means comprising a brake hanger jaw carried by and arranged to move about the axis of said pivot means for supporting a brake shoe, means arranged to move vertically relative to said truck upon an application of a load to said truck, and means connecting said vertically movable means to said pivot carried means so as to move said jaw about said pivot means for maintaining a constant relationship between said brake shoe and wheel.

15. In a railway truck having a resiliently mounted side frame carried by a journal box and a wheel, the combination of, a bracket formed integrally with a column of a side frame and extending inwardly of the truck therefrom, a pivot pin carried by said bracket, means carried by said pivot pin and arranged to move relatively to said bracket, a jaw facing toward said journal box and in said first named means, said jaw supporting a brake shoe, means carried by said side frame adjacent said journal box and slidably connected to said journal box adjacent the vertical axis thereof, and link means pivotally connecting said first named and last named means for maintaining a constant relationship between said brake shoe and wheel.

16. In a railway truck having a side frame resiliently supported by a journal box and a wheel, the combination of, means carried by and arranged to move relative to said side frame, said means including a brake hanger jaw for supporting a brake beam, pivot means associated with said journal box adjacent the lower extremity

thereof, and diagonally disposed means connected to said pivot means and brake hanger jaw so that a movement of said side frame in one direction will be reflected in said brake hanger jaw in an opposite direction for maintaining a substantially constant relationship between said brake beam and wheel.

17. In a railway truck having a side frame resiliently supported by a journal box and a wheel, the combination of, means carried by and arranged to move relatively to said side frame, said means comprising a support for a brake beam, means spaced below said first named means and being associated with said journal box, and inclined means extending from said journal box associated means upwardly toward said support for rotating the latter in response to a vertical movement of said side frame relative to said journal box for maintaining a substantially constant relationship between said brake beam and wheel.

18. In a railway truck having a side frame resiliently supported by a journal box and a wheel, the combination of, movable means carried by and adjacent to a top of said side frame intermediate the ends thereof and comprising a support for a brake beam, means associated with said journal box and being spaced horizontally from and below said first named means, and rigid means connecting both of said means so as to move said support relative to said side frame during a vertical movement of the latter for maintaining a substantially constant relationship between said brake beam and wheel.

19. In a railway truck having a side frame resiliently supported by a journal box and a wheel, the combination of, movable means carried by and adjacent to a top of said side frame intermediate the ends thereof and comprising a support for a brake beam, means associated with said journal box and being spaced horizontally from and below said first named means, and a link pivotally connected to both of said means so as to move said support relative to said side frame during a vertical movement of the latter for maintaining a substantially constant relationship between said brake beam and wheel.

20. In a railway truck having a side frame resiliently supported by a journal box and a wheel, the combination of, a bracket integral with a column of said side frame and extending horizontally therefrom, means pivotally mounted on said bracket and including a support for a brake beam, means associated with a lower extremity of said journal box, and rigid means pivotally connected to both of said means so as to move said support relative to said bracket during a vertical movement of said side frame relative to said journal box for maintaining a substantially constant relationship between said brake beam and wheel.
